UNITED STATES PATENT OFFICE.

THOMAS M. TOPP, OF RICHMOND, CALIFORNIA.

STAMPING AND GRINDING MILL.

No. 877,615.

Specification of Letters Patent.

Patented Jan. 28, 1908.

Application filed May 28, 1907. Serial No. 376,080.

To all whom it may concern:

Be it known that I, THOMAS M. TOPP, a citizen of the United States, residing at Richmond, in the county of Contra Costa and 5 State of California, have invented new and useful Improvements in Stamping and Grinding Mills, of which the following is a specification.

This invention relates to stamping and 10 grinding mills, such as are commonly used for reducing metalliferous ore to pulp, the object of the invention being to provide a mill of this character which will be economical in power and have a large capacity in 15 proportion to the cost of the mill, in which the waste in replacing the worn shoes and dies shall be reduced to a minimum, which will permit of the ready removal of the dies therefrom, and in which the mortar can be 20 easily cleaned up and the residue of the pulp and amalgam easily removed.

In the accompanying drawing, Figure 1 is a broken side view of the mill, the pestle being partly broken away; Fig. 2 is a central 25 vertical section thereof; Fig 3 is broken vertical section on the line 3—3 of Fig. 1.

Referring to the drawing, 1 indicates the mortar which, in general construction, is similar to those now used in stamp mills and 30 has discharge openings for the pulp at the front, at the back, and at the two ends, with grooves 2 for the screens 3. Around the base of the mortar is a trough 4 to receive the pulp, said trough sloping downwards to one end 35 of the mortar, so as to deliver the pulp at that end. Supported upon upward extensions 5 at the ends of the mortar is a central rail 6, forming a guide for a pestle 7. The pestle is formed of a single piece of cast iron 40 and is somewhat fan shaped in form, being narrow at the top, so that the greater part of its weight is in the lower portion, and, in order to vary the weight according to the hardness of the ore to be crushed, the upper 45 portion of the pestle is formed with a chamber 8, which can be filled with a greater or less quantity, as may be desired, of heavy metal. Said upper portion is open at the top and at the ends to permit the rail 6 to 50 pass therethrough, and is provided with pairs of rollers 9, which roll against said rail 6 in the movement of the pestle and guide the latter in its movement with little friction. Said pestle is rocked from any suitable portion 55 of power applied to a cross pin or shaft 10 secured in the upper end of the pestle.

The lower portion of the pestle is formed with an ore distributing cavity 12 to receive the ore which is to be crushed, said chamber being open at one side, as shown at 13, to 60 permit the ore to be fed into said chamber by means of a hopper 14 extending through a side of the mortar. From said chamber 12 lead channels 15, of which there are four in number, said channels passing into the 65 spaces between five shoe holders 16, which are rounded or convex at the bottom, and to which are attached, by means of wooden wedges in the usual manner, the tapering stems 17 of shoes 18. Said shoes 18 are con- 70 vex or rounded on the lower sides to fit in concave dies 19 which are supported in sockets 20 in the base of the mortar. Through the series of sockets extends a central longitudinal groove or trough 21. This 75 trough serves two purposes. It enables any die to be readily removed by inserting a bar or lever beneath the end of the die, and it furnishes a ready means for removing the residual pulp, particles of broken rock, and 80 amalgam. For this purpose the lower end of the groove is continued in the form of a conduit 22 passing through the end of the mortar and which is normally closed by a plug 23. By removing the plug the residual mat- 85 ter can be allowed to flow out into the trough. The sides of the pestle are formed at their lower edges with splashes 24, which curve outwards and upwards, the function of which is to splash the pulp against the screens in 90 the hopper, thereby effecting a more rapid discharge of the pulp through the screens.

The form of the shoes and dies is an important feature of this invention. The shoes are made of uniform thickness, as are 95 likewise the dies, and the result is that said shoes and dies wear evenly, so that when they are worn down and have to be discarded there is substantially no waste of metal. As these shoes and dies are made of high-priced 100 hardened steel, the saving thus effected is an important consideration.

I claim:—

1. A stamping and grinding mill comprising a mortar, a row of concave dies therein, a 105 pestle having a corresponding row of convex shoes at its lower end, and means for imparting a rocking motion to said pestle in the plane of said row, the mortar and pestle being provided with devices arranged to engage 110 each other to maintain the pestle in an upright position while so rocking, one of said

devices being capable of rotary motion, for the purpose of reducing fraction, substantially as described.

2. A stamping and grinding mill comprising a mortar, a row of concave dies therein, a pestle having a corresponding row of convex shoes at its lower end, and means for imparting to said pestle a rocking motion in the plane of said row, said pestle being formed 10 with a chamber for variably weighting the pestle, and with an ore distributing cavity below said chamber, said cavity having a supply opening at the side of said pestle, and said pestle having channels radiating from 15 said distributing cavity to conduct the ore between the shoes, substantially as described.

3. A stamping and grinding mill comprising a mortar, a row of concave dies therein, a pestle having a corresponding row of convex shoes at its lower end, and means for imparting a rocking motion to said pestle in the plane of said row, the bottom of the mortar below the dies being formed with a central longitudinal channel, substantially as de- 20 25 scribed.

In testimony whereof I have hereunto set my hand in the presence of two subscribing witnesses.

THOMAS M. TOPP.
